UNITED STATES PATENT OFFICE.

PETER SHARP, OF PERTH, SCOTLAND.

MEANS FOR STOPPING THE DELIVERY OF ROVING IN SPINNING-MACHINES.

1,304,610.

Specification of Letters Patent.

Patented May 27, 1919.

Application filed February 4, 1919. Serial No. 275,016.

To all whom it may concern:

Be it known that I, PETER SHARP, of Perth, Scotland, spinner, a subject of the King of Great Britain and Ireland, have invented certain new and useful Improvements in and Relating to Means for Stopping the Delivery of Roving in Spinning-Machines, of which the following is a specification.

10 This invention relates to a rove stop for spinning machines and primarily embodies improved stop mechanism adapted for dry or wet spinning and for various kinds of fibers, such as those of jute, flax, tow, hemp, 15 cotton and other materials.

It has been previously proposed to provide means both mechanically and electrically controlled or operated for shifting the rove out of the pass of the feed-rolls upon 20 the breakage of the yarn which usually takes place between the drawing-rolls and bobbin and also to lift said rove out of the nip of the drawing rolls, and further to provide 25 rove stop mechanism which includes a balanced feeler adapted to bear lightly on the thread and to coöperate with some form of mechanism which will stop the feed when the thread breaks, but the majority of said devices involve complicated and intricate 30 mechanism liable to fail or get out of order at critical moments.

According to this invention I provide an improved mechanically controlled automatic rove stop of extremely simple construction 35 having a minimum number of parts and one of such efficiency as to practically guarantee correct operation under all conditions and at all times.

The primary feature of the invention lies 40 in the combination with such a substantially balanced feeler, of a gravity operated member which coöperates with the feeler in such a manner that on breakage of the thread, the feeler energizes and then releases said 45 gravity member, and the latter acts to release or permit actuation of an element for shifting the rove to non-feeding position.

A further feature of the invention comprises novel mechanism co-acting with the 50 feeler and gravity member whereby the rove shifting member is released and on return to normal position also acts to return said gravity member to active position.

The invention further comprises novel features of construction, arrangement and combinations of parts all hereinafter fully de-

scribed and specifically pointed out in appended claims.

A practical embodiment of the invention which is applicable to any conventional type 60 of spinning machine, is represented in the accompanying drawings in which Figure 1 is a sectional side elevation of the mechanism in normal position; Fig. 2 is a front elevation of same; Fig. 3 is a similar view to 65 Fig. 1, showing the position of the parts of the mechanism after breakage of the thread; Fig. 4 is a partial front view of Fig. 3. Fig. 5 is a perspective detail view on an enlarged scale, Fig. 5^a is a plan view of a catch and 70 associated elements, parts being broken away, and Figs. 6 to 9 other detail views of parts hereinafter referred to.

The rove shifting member is in the form of an arm or lever 1 pivoted as at 2 in the 75 upper plate 3^a of a casing 3 inclosing the mechanism and provided at its outer end with a rove guide 4 and rove threading device 4^a all disposed above or adjacent the feed-rolls 5, each of which is provided with 80 a toothed or serrated peripheral portion 6, and one or both having a circumferential groove 7. The lever 1 is adapted, in the manner hereinafter described, to move about its pivot 2 and swing the rove α which 85 passes through the rove-guide from between the nip or serrated parts 6 of said feed-rolls, in which it is shown in Figs. 1 and 2, into the circumferentially grooved part 7 of said rolls as indicated in Figs. 3 and 4 where no 90 traction is exerted on the rove. Below the feed-rolls is disposed a pair of drawing rolls 8 and the flier 9, with bobbin 9^a, and between these two last mentioned elements a convenient part of a "feeler" or the like 10 95 bears on the thread α^1 extending between said drawing rolls and flier.

The general construction so far described is common to many forms of rove-stop mechanism but to now turn to the characteristic features of the present invention. The aforesaid "feeler" is in the form of a rod 11 having at its lower end a curved finger 12 which bears upon the thread, the rod being freely pivoted at 12^a in bearings 13 in the 100 casing 3 and its opposite end being bent within the casing and provided with a pivoted trip 14 (see also Fig. 6) having an angular nose 15 and under the action of a spring 16, the trip being normally maintained in alinement with the rod by means of a stop-pin 17. The construction and

mounting of the feeler rod is such that it is substantially balanced and exerts only a very slight pressure on the thread.

The said nose 15 of the trip 14 normally engages under a slide or plate 18 (see also Fig. 8) projecting laterally from the lower end of a weight 19 freely suspended in the casing on a pivot pin 20 (see also Fig. 5), said weight being provided adjacent its pivot with a laterally projecting pin 21, adapted to bear against one arm of a trigger 22 freely pivoted on a stud 23, the other arm of said trigger engaging a catch 24 under the action of a spring 25 and having a shoulder 26 which under normal conditions engages behind a snag 27 depending from the rove-shifting lever 1, whereby the latter is maintained in the operating or feeding position shown in Figs. 1 and 2. The aforesaid weight 19 is also provided with a second abutment 28, having an inclined and shouldered face 29 and which co-operates with the lower end of a weighted tumbler 30, pivoted at the side of the casing on a stud 30^a in a plane at right angles to the weight 19. The upper end of said tumbler coats with a finger 31 on the end of a gravity trip 32 pivoted at 33 to the inner end of the rove-shifting lever 1 for a purpose hereinafter explained.

The operation of the mechanism so far described is as follows:—

When the thread x^1 breaks, the feeler-rod 11 is released, and its lower member swings down by gravity about the pivot 12^a, its upper member at the same time being raised. This movement of the feeler-rod causes the nose 15 of the spring trip 14 to slide along the under face of the weight plate 18 (see position Fig. 1) and rocks the weight 19 about its pivot 20 to the left, or in other words lifts same, and during this movement the shouldered face 29 of abutment 28 releases the tumbler 30 so that it falls backward under the influence of its weight free of such abutment. The lifting of the weight continues until the nose 15 slips off the end of said plate 18, whereupon the weight 19 swings back to the right, to the position shown in Fig. 3 and the pin 21 acts against the trigger 22 which in turn releases the spring catch 24 from the snag 27 on lever 1, thus allowing the latter to be swung sharply into inactive or non-feeding position under the action of a spring 34 which bears on the rear of the lever. The rove-shifting lever 1 on being thus released forces the rove x over and immediately said rove is clear of the serrated part 6 of the feed-rolls, and passes into the grooved part 7 thereof the rove engages a toothed or roughened projection 35 (see Fig. 7) on the outer end of the top-plate 3^a of the casing 5 (Fig. 8), so that a bend, deflection or equivalent is formed in the rove as shown in Fig. 4, which causes

same to be slightly lifted out of the nip of the drawing rolls if the break has taken place close thereto.

When the operative desires to "piece" the thread x^1 , the latter is taken up from the bobbin 9^a in the usual way and when ready to allow the rove to be again fed by the feed-rolls the lever 1 is moved back by hand into operating or feeding position where it will be held to continue the feeding by the re-engagement of the shoulder 26 of the spring catch 24 with the snag 27 of said lever and by the weight 19 being held against active movement by the weighted tumbler 30 above mentioned, this latter operation being performed by means of the trip finger 31 on the lever 1 forcing forward the upper end of the tumbler, the lower end of which consequently co-operates with the inclined face 29 of the weight abutment 28 to return the weight to normal position and then engages behind the shoulder of said inclined face 29, thus locking the weight in said normal position.

When the operative has pieced the thread x^1 and again moved the feeler finger 12 into engagement therewith, the nose 15 of the spring-trip 14 will reengage under the plate 18 of the weight 19, moving same sufficiently to release the tumbler 30, all the parts being thus returned to original positions ready to act in the manner above described should the thread again break.

The aforesaid plate 18 may with advantage be made slightly curved at its ends in opposite directions, as shown in Fig. 8, being curved upward at the right hand end as at 36 to assist the sliding off of the nose 15 and curved downward at its left hand end as at 37 to bring the nose, and consequently the feeler, to rest. Such a formation will render the mechanism extremely sensitive and produce more definite swing of the weight and consequent sharp movement of the lever 1.

When the motion of the spinning frame 110 is stopped for removing the full bobbins and placing empty ones in position, or for other reason, I may provide means for putting the rove-shifting mechanism out of action or locking same and the means shown in the drawings for the purpose comprises a cam 40, shown at the back of the mechanism, adapted to act on a spring plunger 41 which extends through the casing 3 and engages any suitable part of the mechanism, the part in the present instance being the weighted tumbler 30, the plunger making contact with the curved face 30^b thereof, thus preventing it from becoming released from the weight abutment 28, and consequently locking the weight and all other co-operating parts, it being understood that the top of the tumbler 30 drops back, or swings clockwise in Fig. 6, which is prevented by plunger 41 being disposed in ad-

vance of the face 30^b. It will be understood that one of said cams 40 and plungers 41 is provided for each spindle and corresponding rove-shifting mechanism on the spinning frame and all are capable of being actuated at the same time by mounting the cams on a shaft 42 extending across the frame and capable of being manually operated to hold the mechanism inactive until the operative effects release by moving the feeler rod 11 in a reverse direction or to the left as far as it will extend, (a spring 43 being provided to prevent straining of the feeler) and then allowing its finger 12 to 10 engage the thread whereupon the mechanism is again ready for operation.

The cam motion above described is only for use when the frame is stopped, as otherwise the "feeler" in moving back and the thread being disengaged, all the stop motion mechanism would come into operation.

A second cam motion (one for each spindle and capable of simultaneous operation when the frame is re-started) may also be provided, such motion being shown as comprising a shaft 44 on which is mounted a cam 45 acting on the forked end of a double armed lever 46 pivoted at 47 to a suitable support (not shown), the other arm of said lever carrying a grooved roller 48 which engages the feeler rod 11. The purpose of this motion is to move all the feelers past their normal position to that indicated in broken lines in Fig. 1 and then allow them to return to reengage the threads, thus dispensing with the usual operation in which the operative has to separately handle and move the feeler rods to bring them into desired position before re-starting the frame.

I also propose to dispense with the usual separate thread-plate or guide between the drawing rolls and the flier and to produce this guide by means of an eye formed at a convenient position on the feeler for instance at the outer end of the finger 12 thereof as shown at 50 in Fig. 9 the thread passing through said eye so that when the thread breaks the action of the mechanism will be the same as above described.

I do not limit myself to the exact construction arrangement or combination of parts above described and illustrated in the accompanying drawings since the same may be varied within limits prescribed by the appended claims without departing from the spirit of the invention.

What I claim as my invention and desire to secure by Letters Patent of the United States is:—

1. Rove stop mechanism comprising in combination a rove shifting element normally in rove feeding position, a balanced feeler adapted to bear on the thread and a gravity operated member, the latter and the feeler being adapted to cooperate whereby

on breakage of the thread, the gravity member is first lifted by the feeler and then released therefrom, said gravity member then acting to permit actuation of the rove shifting element to non-feeding position. 70

2. Rove stop mechanism comprising in combination a pivoted rove shifting member, a substantially balanced feeler adapted to bear at one end with a minimum of pressure on the thread, a gravity operated weight coöperating with the opposite end of said feeler, said weight being first lifted by the feeler and then released therefrom, and means adapted to hold the rove-shifting member normally in feeding position, 80 said means being actuated by the weight on breakage of the thread to permit movement of said shifting member to non-feeding position.

3. Rove stop mechanism comprising in combination a spring actuated rove shifting member, a balanced feeler adapted to bear on the thread, a gravity operated weight adapted to be first lifted by said feeler and then released therefrom, trigger 90 mechanism between the weight and shifting member and engageable by the weight and a spring catch normally holding said member in feeding position against the action of its actuating spring, said trigger mechanism and spring catch coöperating under the action of the weight on breakage of the thread to release the shifting member and permit it to move to non-feeding position. 95

4. Rove stop mechanism for spinning machines comprising in combination a rove-shifting member normally in rove-feeding position, a balanced feeler adapted to bear on the thread, a gravity operated member coöperating with the feeler and adapted to 100 be first lifted thereby and then released therefrom, and a locking device for said gravity operated member including a loaded tumbler adapted on energization of the gravity operated member by the feeler on 110 breakage of a thread to release the said gravity member to permit said rove-shifting member to move to the non-feeding position. 105

5. Rove stop mechanism for spinning machines comprising in combination a rove-shifting member normally in rove-feeding position, a balanced feeler adapted to bear on the thread, a gravity operated member coöperating with the feeler and adapted to 115 be first raised thereby and then released therefrom and a locking device for said gravity operated member including a loaded tumbler adapted on energization of the gravity operated member by the feeler on 120 breakage of a thread to release the said gravity member to permit said rove-shifting member to move to non-feeding position, said tumbler also serving to restore the 125 gravity member to normal position when the 130

rove-shifting member is returned to feeding position.

6. Rove stop mechanism comprising in combination a rove-shifting member, a substantially balanced feeler adapted to bear at one end with a minimum of pressure on the thread, a trip device at the opposite end of said feeler, a gravity operated weight having means coöperating with the trip device on the feeler whereby on breakage of the thread the weight is first lifted by the feeler and then released therefrom, and means adapted to hold the rove shifting member in feeding position, said means being actuated by the weight to permit movement of the shifting member to non-feeding position.

7. Rove stop mechanism comprising in combination a rove shifting member, a substantially balanced feeler adapted to bear at one end with a minimum of pressure on the thread, a trip device at the opposite end of said feeler, a gravity operated weight, a plate on said weight coöperating with the trip device on the feeler, and having oppositely curved ends to assist the sliding off of the trip device at one end and retard its sliding movement at the other end, such weight on breakage of the thread being first lifted by the feeler and then released therefrom and means adapted to hold the rove shifting member in feeding position, said means being actuated by the weight on its release to permit movement of said member to non-feeding position.

8. Rove stop mechanism comprising in combination a rove-shifting member normally in rove feeding position, a balanced feeler adapted to bear on the thread, a gravity operated member coöperating with the feeler whereby on breakage of the thread the feeler first lifts and then releases said gravity member and the latter then acts to cause movement of the rove shifting member to non-feeding position, and means for rendering the aforesaid mechanism inoperative on stoppage of the machine, comprising a cam motion and a spring plunger applied to part of the mechanism.

9. In a rove stop mechanism for the spindles of spinning machines, the combination of a rove shifting member normally in rove feeding position, a balanced feeler adapted to bear on the thread, a gravity member coöperating with the feeler whereby on breakage of the thread the rove shifting member may be moved to non-feeding position, means applied to each spindle of the machine for rendering the rove stop mechanism inoperative on stoppage of the machine, comprising a cam-motion and a spring plunger applied to part of the mechanism, and devices for actuating all said last mentioned means simultaneously.

10. In a rove stop mechanism for the spindles of spinning machines the combination of a rove shifting member normally in rove feeding position, a balanced feeler adapted to bear on the thread, a gravity member coöperating with the feeler whereby on breakage of the thread the rove shifting member may be moved to non-feeding position, and means for shifting a plurality of feelers in a machine beyond normal position and then allowing them to return to reengage the threads, said means comprising a separate cam motion for each spindle and devices for actuating all said cam motions simultaneously.

11. In a rove stop mechanism the combination of a rove shifting member normally in rove feeding position, a balanced feeler having at one end a thread guide in the form of an eye, and a gravity operated member coöperating with the opposite end of the feeler whereby on breakage of the thread the feeler first lifts and then releases said gravity member and the latter acts to cause movement of the rove shifting member to non-feeding position.

In witness whereof I have signed this specification in the presence of two witnesses.

PETER SHARP.
